UNITED STATES PATENT OFFICE.

ROBERT KLENA, OF ADRIAN, PENNSYLVANIA.

SHIP'S TABLE.

1,150,769.

Specification of Letters Patent. Patented Aug. 17, 1915.

Application filed April 20, 1915. Serial No. 22,578.

To all whom it may concern:

Be it known that I, ROBERT KLENA, a citizen of the United States, residing at Adrian, in the county of Armstrong and State of Pennsylvania, have invented certain new and useful Improvements in Ships' Tables, of which the following is a specification.

This invention relates to certain new and useful improvements in ships' tables.

The primary object of the invention is to provide a table especially adapted for use upon shipboard and arranged so that the table top will remain at all times horizontally positioned regardless of the movement of the ship.

A further object is to provide a table with a balanced top, the same being normally maintained horizontally positioned by means of a gravity pendulum, thus preventing the spilling or slipping of articles which are positioned on the top of the table.

A still further object is to provide a ship's table that is cheap and easy to manufacture and which at the same time possesses great strength and has a positive stabilizing means for maintaining the table top uniformly horizontal.

With these general objects in view and others that will appear as the nature of the invention is better understood, the same consists in the novel combination and arrangement of parts hereinafter more fully described, illustrated in the accompanying drawings, and pointed out in the appended claims.

In the drawings forming a part of this application and in which like-designating characters refer to corresponding parts throughout the several views:—Figure 1 is a perspective view of the present device with the table top illustrated in dotted lines. Fig. 2 is a side elevation of the complete table. Fig. 3 is a horizontal sectional view taken upon line III—III of Fig. 2. Fig. 4 is another side elevation of the device taken from a point at right-angles to that of Fig. 2. Fig. 5 is a sectional detail view taken upon line V—V of Fig. 2, and Fig. 6 is a vertical sectional detail view taken upon the plane of one of the return springs of the device.

Referring more in detail to the drawings, the invention broadly consists of a table having a top 10, herein illustrated as circular, mounted upon a frame or support 11 and normally maintained horizontal. The said

supporting frame 11 consists of oppositely arranged A-shaped frames 12 each of the said frames having two legs 13. A connecting bar 14 is secured between the top cross-heads 15 of the said frames 12 and has a central disk 16 centrally provided with a circular bearing socket 17 in its upper face, while angularly extending struts 18 connect the frames with the bar 14 at opposite sides of the said disk. A top disk 19 substantially of the same diameter as the afore-mentioned disk 16 is provided with a central projecting post 20 upon its lower face, the said post having a substantially semi-spherical free end 21 adapted for seating in the socket 17 for supporting the disk 19 thereon. The table top 10 is flatly positioned upon the upper face of the top disk 19 concentric therewith and is secured thereto by means of bolts 22 extending through the table top and also through opposite lugs 23 of the top disk 19, the said lugs being normally positioned in the same longitudinal plane as the aforementioned bar 14.

A counterweight 24 acting after the manner of a pendulum is herein illustrated in the form of a solid frustrated cone being suspendingly attached to the said upper disk 19 by means of upwardly and outwardly curving arms 24' having their lower ends secured at opposite points adjacent the top of the pendulum and their upper ends secured within opposite lugs 25 of the said disk 19 and at intermediate points between the afore-mentioned lugs 23 thereof.

A plurality of coiled compression springs 26 are arranged concentric with the normal position of the post 20 and connecting the upper and lower disk, the said springs having their opposite ends secured to transverse pins 27 arranged in opposite sockets 28 and 29 in the adjacent faces of the said upper and lower disks 19 and 16 respectively.

From this detailed description of the device, it will be seen that the pendulum 24 will maintain the post 20 in its normal vertical position and regardless of any inclination or tipping of the supporting frame 11 as occasioned for instance by the rolling or tipping of the ship upon which the table is provided. This constant tendency to maintain the post 20 vertical results in normally maintaining the top disk 19 and the table top 10 horizontal, while the pendulum is further assisted in this function by the return or compression springs 26 heretofore

described. Additional positioning springs 30 are connected at four points 31 upon the outer surface of the pendulum 24 and normally extend radially therefrom and having 5 their outer ends attached as at 32 to the adjacent inner edges of the frame legs 13.

This table may be made of any desired material such as wood although the pendulum 24 may be suitably weighted or formed 10 of metal if desired, it will be seen that a strong serviceable device is thus arranged for accomplishing the designated results.

While the form of the invention herein shown and described is what is believed to 15 be the preferred embodiment thereof, it is nevertheless to be understood that minor changes may be made without departing from the spirit and scope of the invention as claimed.

20 What I claim as new is:—

1. A table comprising a supporting frame having a central socket, a supporting disk, a table top concentrically secured to the upper face of the said disk, a central projecting post upon the under side of the said disk and provided with a semi-spherical free end normally seated within the said socket, a pendulum, outwardly curved spanning arms suspendingly connecting the said pendulum 25 with the said disk, and resilient returning means between the said frame and pendulum and disk.

2. A table comprising a frame having a central socket a top-supporting disk, a centrally-positioned post attached to the lower face of the said top-supporting disk and 30

having its free end seated within the said socket, a balancing pendulum beneath the said supporting disk, a table top on said disk, and outwardly curved connecting arms 40 spanning the said frame and connecting the said pendulum and table top.

3. A table comprising a frame having a top connecting bar provided with a central disk having a central socket in its upper 45 face, an upper disk, a table top secured to the said upper disk, means carried by said upper disk and seated within the said socket, and balancing means suspendingly attached to the said upper disk.

4. A table comprising a frame having a top connecting bar provided with a central disk having a central socket in its upper face, an upper disk, a table top secured to the said upper disk, a central projecting 50 post carried by the lower face of the said upper disk and having a semi-spherical free end seated within the said socket, connecting springs concentrically arranged between the adjacent faces of the said two disks, a counterweight positioned beneath the said central disk, and outwardly curved connecting arms between the upper end of the said counterweight and opposite sides of the said upper disk.

55 In testimony whereof I affix my signature in presence of two witnesses.

ROBERT KLENA.
